UNITED STATES PATENT OFFICE.

GEORGE F. BOND, OF TROY, NEW YORK.

CAR-BRAKE.

SPECIFICATION forming part of Letters Patent No. 268,610, dated December 5, 1882.

Application filed September 15, 1882. (No model.)

To all whom it may concern:

Be it known that I, GEORGE F. BOND, of Troy, Rensselaer county, New York, have invented a new and Improved Car-Brake, of which the following is a full, clear, and exact description.

The object of my invention is to provide a new and improved car-brake which can easily be applied at any time from any part of the train, and which need not be operated by manual labor.

The invention consists in a car-brake formed of brake-shoes attached to the ends of a toggle-lever connected by means of an elbow-lever with a longitudinally-movable rod held on the bottom of the car and provided with a bumper-head at one end. The opposite car is provided with a vertically-adjustable bumper-head, and when the same is lowered and the cars are caused to bump together by checking the speed of the engine, the rod is moved longitudinally, the joint of the toggle-lever is pressed downward, and the brake-shoes are pressed against the wheels.

Reference is to be had to the accompanying drawing, forming a part of this specification, in which two cars provided with my improved brake are shown in longitudinal sectional elevation.

The brake-shoes A are pivoted to the lower ends of toggle-levers B, the upper ends of which are pivoted to each other, the pintle B' passing through a vertical slot, a, in a guide plate or frame, C, projecting downward from the bottom. Near the brake-shoes a rod, D, is pivoted to each lever B, and the upper ends of the said rods are pivoted to the car-bottom.

An elbow or angle lever, E, is pivoted at its angle to a plate or frame, E', projecting downward from the car-bottom, and the end of the lower arm of the said elbow-lever E is pivoted on the pintle B', and the end of the upper or vertical arm of the said elbow-lever is pivoted to a horizontally-movable rod, F, held on the car-bottom, and provided at one end projecting from the end of the car with a buffer-head, G. A spring, H, coiled around the rod F, presses the end provided with the head G from the end of the car. The other end of the rod F is attached to one end of a chain, J, which is attached to a vertical brake-shaft,

K, of the usual construction. On the end provided with the brake-shaft K the car is provided with a vertically-sliding bar, L, to the lower end of which a rectangular head or buffer, M, is fastened, which projects from the end of the car. By means of the chain or rope N the sliding bar L is connected with a rope or chain, O, running along the roofs of all the cars. The rope N passes between the grooved pulleys P, over which the rope O also passes, so that if the rope O is drawn from either end of the train the rope or chain N can pass over one of the pulleys P, the mechanism to be so arranged and the shoes so connected that the brakes on all wheels—that is, both sides of the cars—will be applied at the same time.

The operation is as follows: The rope O is held taut, so that the bars L and the heads M thereon will be held raised, and the rope O is secured in the locomotive-cab to remain taut. If the engineer wishes to apply the brakes, he releases the cord O, upon which the bars L and the heads M slide downward. If, then, the speed of the locomotive is checked, the cars will bump against each other and the bumper-heads M strike against the beads G of the rods F, which are moved in the direction of the arrow a'. Thereby the pivot B' will be pressed downward by the elbow-lever E, and the levers B will press the brake-shoes A against the wheels and the brakes will be applied. As soon as the cars are separated or the bars L and heads M are raised the springs H press the headed ends of the rods F outward again. The brakes can also be applied by winding the chains J on the shafts K, as the rods F will be moved in the direction of the arrow a' thereby, and this will be found to be of great service in shunting cars. The rope O can be released from either end of the train, but preferably is to be controlled by the engineer. When the train is in motion the heads can be lowered, so that if a train runs off the track or an axle breaks, &c., the brakes will be immediately applied automatically.

Having thus described my invention, I claim as new and desire to secure by Letters Patent—

1. In a car-brake, the combination of a toggle-lever having brake-shoes and attached to one end of a pivoted elbow-lever, with which the pintle of the toggle-lever is connected,

and a sliding rod extending longitudinally through the car and beyond it, and provided with a buffer-head, said buffer-head adapted to be acted upon by a lowered buffer of the opposite car as the movement of the engine is checked.

2. In a car-brake, the combination, with the toggle-lever B, with its pintle B' moving in the slotted guide C a, of the brake-shoes A, attached to the ends of the same, the elbow-lever E, the rod F, and the pivoted rods D, pivoted to the bottom of the car and to the toggle-lever B, substantially as herein shown and described, and for the purpose set forth.

15 3. In a car-brake, the combination, with the toggle-lever B, with its pintle B' moving in the slotted guide C a, of the brake-shoes A, the elbow-lever E, the rod F, the rods D, pivoted to the bottom of the car and to the toggle-lever B, and the spring H, substantially as herein shown and described, and for the purpose set forth.

4. In a car-brake, the combination, with the toggle-lever B, with its pintle B' moving in the 25 slotted guide C a, of the brake-shoes A, the elbow-lever E, the rod F, the spring H, the rods D, pivoted to the bottom of the car and to the toggle-lever B, and the buffer-head G, sub-

stantially as herein shown and described, and for the purpose set forth.

5. In a car-brake, the combination, with the toggle-lever B, of the brake-shoes A, the elbow E, the rod F, the spring H, the rods D, the buffer-head G, the chain J, and the vertical brake-shaft K, substantially as herein shown 35 and described, and for the purpose set forth.

6. In a car-brake, a toggle-lever carrying brake-shoes and connected by an angle-lever with a longitudinally-movable rod on the bottom of the car, combined with a vertically-adjustable buffer-head in the opposite car, substantially as described and set forth.

7. In a car-brake, the combination, with a toggle-lever carrying brake-shoes and connected by an elbow-lever with a longitudinally-movable rod on the bottom of the car, of a vertically-movable buffer-head on the opposite car, and a rope, chain, or rod running along the roofs of the cars and connected with the said vertically-movable buffer-head, substantially 45 as herein shown and described, and for the purpose set forth.

GEORGE F. BOND.
